UNITED STATES PATENT OFFICE.

JOHN THOMAS SENTENEY, OF BLOCKSBURG, CALIFORNIA.

PLOW.

SPECIFICATION forming part of Letters Patent No. 373,489, dated November 22, 1887.

Application filed August 11, 1887. Serial No. 246,713. (No model.)

To all whom it may concern:

Be it known that I, JOHN THOMAS SENTENEY, a citizen of the United States, residing at Blocksburg, in the county of Humboldt 55 State of California, have invented certain new and useful Improvements in Plows; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to plows of that class 15 which have reversible plowshares, and are designed to plow across the field in each direction, making parallel furrows, and turning the earth in the same direction. The plowshares of such plows are reversed at the end of a fur- 20 row previous to returning, and are held in their changed position by suitable catches, all of which are more or less objectionable, because of a too great number of parts, easily gotten out of repair, inconvenient of operation, or 25 some such similar objection.

The present invention has for its object to obviate all objections against prior devices, and provide a simple, compact, and efficient means for holding the plowshare when re- 30 versed, and which is convenient of operation for releasing the plowshare, and engaging it, and which is not liable to get out of repair.

The improvement consists in the novel and peculiar construction and combination of 35 parts, which will be more fully hereinafter set forth, claimed, and shown in the annexed drawings, in which—

Figure 1 is a perspective view of a plow embodying my invention; Fig. 2, a detail sectional view about on the line X X of Fig. 1, 40 looking in the direction of the arrow, showing the plowshare reversed by dotted lines; Fig. 3, a top view of the front portion of the standard and the lock-bolt carried thereby, and Fig. 4 a sectional detail view on the line Y Y 45 of Fig. 1.

The plow-beams A, handles B, reversible plowshare C, landside-bars D, and standard E are old and well-known constructions and arrangements, and are shown simply to illustrate the application of my invention.

The upper end of the front portion, E', of the standard is extended to the front and rear, forming bearings e and e', which bear against the under side of the beam, and is held thereto by the keeper F, and the yoke f, seated in a groove or recess in one of the bearings and held to the keeper by the nuts f'.

The catch or lock for fastening the plow-share in either of its adjusted positions is composed of the rock-shaft G, journaled in bearing e', and having hook-shaped heads g, which are adapted to be turned down and engage with the landside-bars D. The heads are one width, and are larger than the shaft to overlap 60 the sides of the bearing e', and prevent any longitudinal movement of said shaft. To facilitate the mounting of the shaft the bearing e' is provided with a removable cap portion, e'', between which and the bearing proper, e', 70 the shaft is journaled. The arm H, extending rearwardly from the rock-shaft, terminates in an eye, h, to which the lower end of the operating-rod I is loosely connected. This rod extends upward within convenient reach of the 75 driver, and is held to one of the handles by keeper i. A movement of rod I up or down rotates rock-shaft G and engages or disengages its head from the landside-bar of the plowshare, whichever is desired.

The rock-shaft, the hook-shaped heads, and the arm, for the sake of economy, will be made of a single casting. However, I do not restrict myself to such construction, as it is evident that they may be made separate and secured 85 together.

Having thus described my invention, what I claim, and desire to secure by Letters Patent, is—

1. The combination, with the plow-beam 90 and the reversible plowshare, of the rock-shaft having hook-shaped ends journaled transversely of the beam, and means, substantially as described, for operating said rock-shaft for locking the plowshare in either position, substantially as set forth.

2. The combination, with the plow-beam, the standard having the upper end of its front portion extended front and rear, forming bearings which are grooved, the yoke seated in 100 the groove of one of the bearings, and the clip embracing the beam and held to the yoke by

nuts, of the rock-shaft transversely journaled in the other bearing, and having hook-shaped ends, means for operating said rock-shaft, and the reversible plowshare having landside bars, 5 substantially as and for the purpose described.

3. The combination, with the beam, the standard having bearings, the removable cap-plate forming a portion of one of the bearings, the rock-shaft having hook-shaped ends, and 10 an arm projected at right angles therefrom, the operating - rod connected with said arm

and extending within convenient reach, and the reversible plowshare having landside-bars, substantially as and for the purpose specified.

In testimony whereof I affix my signature in presence of two witnesses.

JOHN THOMAS SENTENEY.
